UNITED STATES PATENT OFFICE.

JOSEPH D. RICE, OF PHILADELPHIA, PENNSYLVANIA.

RAILROAD-RAIL SPLICE-PIECE AND CHAIR.

1,158,851.

Specification of Letters Patent.

Patented Nov. 2, 1915.

Application filed June 30, 1915. Serial No. 37,149.

To all whom it may concern:

Be it known that I, JOSEPH D. RICE, a citizen of the United States, residing in the city and county of Philadelphia, State of Pennsylvania, have invented a new and useful Railroad-Rail Splice-Piece and Chair, of which the following is a specification.

My invention consists of a railroad rail splice piece and chair which is composed of members that are adapted to connect adjacent rails and support rails in a firm and desirable manner as will be hereinafter set forth.

It consists also of details of construction as will be hereinafter set forth.

The invention is satisfactorily illustrated in the accompanying drawing, but the important instrumentalities thereof may be varied, as long as they are included in the scope of the claims.

Figure 1 represents a perspective view of a railroad rail splice piece and chair embodying my invention. Fig. 2 represents an end view thereof. Fig. 3 represents a top or plan view thereof, the rails having been removed therefrom. Fig. 4 represents an elevation of the movable cheek piece of the device.

Similar numerals of reference indicate corresponding parts in the figures.

Referring to the drawings, 1 designates a base plate from one side of which rises the cheek piece or clamp 2 integral therewith, and the other side of which is extended outwardly in horizontal direction forming the ledge 3 in whose upper face is the groove or channel 4, whose walls are dovetailed in their nature.

5 designates the cheek piece or clamp which is opposite to the cheek piece or clamp 2, the same being separate from the base plate 1, and having a flat under edge 6 adapted to rest on the base plate 1, and the lower end of the inner side of the cheek piece 5 is recessed as at 7 in longitudinal direction to conform to and rest upon the outer edge portion 8 of the base 9 of the railroad rail 10, which base is seated on the base plate 1.

Depending from the lower end of said cheek piece 5 is the tongue 11 which extends in the longitudinal direction of the cheek piece and is adapted to enter the groove or channel 4, its sides formed according to those of said groove so as to form a dovetailed joint therewith.

The outer side of said ledge has a longitudinally-extending lip 12 rising therefrom and has its inner face curved to accord with the adjacent curved portion of the outer face 63 of the cheek piece 5 and overhang said portion and interlock therewith, which with the tongue 11 and the groove 4 and the dovetailed joint of the latter forms a vise-like and firm connection of said cheek piece 5 65 with the ledge 3, the base plate 1 and the base 9 of the rail 10.

In order to bolt the cheek pieces to the rail the former are provided with ears 13 which extend laterally out from the ends 70 of the upper portion of said cheek pieces and are perforated to receive the bolts 14 which pass through the same and through openings in the web of the rail 10 when by means of nuts 15 said cheek pieces and 75 the rail may be held tightly together, it being noticed that the upper ends of the cheek pieces and of the ears engage the under sides of the head of the rail, and so provide a firm support for said head while 80 adjacent rails are connected by the cheek pieces.

It will be seen that owing to the perforated ears 13, the cheek pieces are not perforated or pierced for the passage of clamping and securing bolts therethrough, and thus the integral nature and consequent strength of the cheek pieces are preserved, while the bolting of the cheek pieces and rail is accomplished close to the under sides 90 of the head of the rails, thus in a great measure serving to prevent spreading of the rail, while the downward pressure of said head on the cheek pieces is distributed to a greater width thereon owing to the increased 95 width of the top of the cheek pieces due to the ears 13 which project beyond the ends of the bodies of said cheek pieces without, however, increasing the lengths of said bodies. Furthermore the ears rest flat 100 against the webs of the rails and are bolted solidly and tightly against the same, while their positions on the sides of the cheek pieces render them most convenient of access for the application and removal of the 105 bolts 14 and nuts 15.

The base plate is extended beyond the ends of the cheek pieces, thus providing lengthened bearing surfaces for the rail on said plate, and the latter is less liable to tip 110 on the ties when the cars pass over the portions of the rails that rest on the base plate

since a greater length of said base plate may rest on the ties. It will be seen also that bond wires when employed, the same extending from one rail to the other, as shown in dotted lines Fig. 1, are in a measure covered by the cheek pieces and so prevented from being drawn-out, cut and abstracted or stolen. It will be noticed also that the cheek pieces are arch-shaped in vertical direction, making the same a strong structure, and the inner faces of said pieces are channeled, which throws them out from the web of the rail, and consequently from said bond wires, preventing current-contact of the latter by the cheek pieces.

Having thus described my invention what I claim as new and desire to secure by Letters Patent, is:—

1. In a railroad splice piece and chair, a base plate, a cheek piece rising from said base plate and engaging the head of a railroad rail to be supported on said base plate, and perforated ears on said cheek piece

projecting longitudinally from the sides of the upper portion thereof for direct attachment to the web of the rail.

2. In a railroad splice piece and chair, a base plate, a cheek piece rising from said plate and being adapted to engage the head of the railroad rail supported on said base plate, and perforated ears on said cheek piece projecting longitudinally from the sides of the upper portion thereof.

3. In a railroad splice piece and chair, a base plate, a cheek piece rising from said base plate and engaging the head of a railroad rail to be supported on said base plate, and means for bolting said cheek piece to said rail, said base plate having its end portions extending beyond the ends of said cheek piece.

JOSEPH D. RICE.
